UNITED STATES PATENT OFFICE.

ALFRED J. BRUMMELER, OF GRAND RAPIDS, MICHIGAN.

DESIGN FOR A SPRAYER-BODY.

SPECIFICATION forming part of Design No. 31,144, dated July 4, 1899.

Application filed February 16, 1899. Serial No. 705,735. Term of patent 7 years.

To all whom it may concern:

Be it known that I, ALFRED J. BRUMMELER, a citizen of the United States, residing at Grand Rapids, in the county of Kent and State of Michigan, have invented and produced a new and useful Design for a Sprayer-Body, of which the following is a specification, reference being had to the accompanying drawings, forming part thereof.

Figure 1 is a plan of my invention, and Fig. 2 is a side elevation of the same.

As shown in the drawings, the leading or material feature of my invention consists of the tank A and the air-cylinder B, the conical tubes C C being in pairs and tapering to small points at the ends immediately over the ends *d d* of the discharge-tubes D.

E represents a support for the ends of the discharge-tubes, and *d'* represents where the discharge-tubes enter the tank A.

20

Having thus fully described my invention, what I claim as new, and desire to secure by Letters Patent of the United States, is—

The design for a sprayer-body as herein shown and described. 25

Signed at Grand Rapids, Michigan, February 7, 1899.

ALFRED J. BRUMMELER.

In presence of—

A. W. JOANNES,
I. J. CILLEY.
